UNITED STATES PATENT OFFICE.

HENRY S. NUNAMAKER, OF CANTON, OHIO, ASSIGNOR TO THE V. L. NEY HAY TOOL COMPANY, OF CANTON, OHIO, A CORPORATION OF OHIO.

HAY-CARRIER.

1,346,242.

Specification of Letters Patent. Patented July 13, 1920.

Application filed February 28, 1919. Serial No. 279,719.

To all whom it may concern:

Be it known that I, HENRY S. NUNAMAKER, a citizen of the United States, residing at Canton, in the county of Stark and 5 State of Ohio, have invented a new and useful Hay-Carrier, of which the following is a specification.

This invention relates to hay carriers and has more especial reference to cross draft 10 hay carriers or that class of carriers in which the elevating rope leads from the carrier in a direction substantially at a right angle to the track along which the carrier is adapted to move.

15 The object of the invention is to provide a hay carrier of the character mentioned with a spring pressed bolt controlled by a lever and arranged to be automatically released when the desired load is attached to 20 the elevating rope locking the elevating rope against movement and locking the sheave.

Another object is to provide a hay carrier 25 in which a spring pressed bolt is moved into position to hold the parts in the loading position by means of the operation of the elevating rope.

With these objects in view the invention consists in the novel construction and arrangement of parts, hereinafter described, 30 illustrated in the accompanying drawings, and particularly pointed out in the appended claims, it being understood that various changes in the form, proportions, size and minor details of construction may be made 35 within the scope of the appended claims, without departing from the spirit or sacrificing any of the advantages of the invention.

The invention thus set forth in general 40 terms is illustrated in the accompanying drawings forming part hereof, in which—

Figure 1 is a side elevation of a carrier embodying the invention, mounted upon a track showing the parts in the unlocked or 45 loading position, the near side of the frame being removed and parts broken away to more fully disclose the construction.

Fig. 2, a section on the line 2—2, Fig. 1.

Fig. 3, a side elevation of the carrier, the 50 inner side of the frame being removed and parts being broken away to more fully disclose the construction, the parts being shown in the locked position assumed when the load is being transported along the track;

Fig. 4, a side elevation of the carrier show-

ing the parts in the unlocked or loading position; and

Fig. 5, a side elevation upon a smaller scale of the carrier showing the rope fall.

A practical embodiment of the invention 60 is disclosed in the accompanying drawings, forming a part of this specification in which similar numerals of reference indicate corresponding parts throughout the several views.

65

The track 1 upon which the carrier is adapted to run may be of any suitable or well known form and is suspended from any substantial support such as the rafters of a barn. The main frame of the carrier is suspended upon the truck frame 2, which is provided at its ends with the rotatably mounted traveling wheels 3 adapted to run upon the track.

70

The main carrier frame is formed of two 75 sides 4 and 5, preferably stamped from sheet metal, connected to each other and held in spaced relation. Strips 6 are attached to the side frames in any approved manner and extend upwardly beyond the frames, the 80 upper extremities of said strips being connected to the head 7, which is carried in the truck frame 2. In this way it will be seen that the carrier with its load is suspended from four traveling wheels, two being arranged at the front and two at the rear. In the lower portion of the main frame and at a point substantially beneath the center of the track is located the main sheave axle 8, which extends transversely from one side 85 frame to the other and upon which is rotatably mounted the main sheave 9. This sheave is preferably of considerable diameter to lighten the draft as much as possible and facilitate the operation of the 90 carrier.

95

Pivots connected to the side frames 4 and 5 upon a transverse bearing having its axis at 10 is the rope locking lever 11 comprising two similar spaced members joined 100 together by means of the bolts 12 and 13. The rope locking lever extends outwardly to one side of the main frame and is provided with a downwardly depending portion 14 in which are carried the rollers 15 and 16, 105 mounted upon the bolts 12. The sheave brake 17 is pivotally mounted upon a suitable axis 18 adjacent the main sheave 9.

The rope grip 19 is preferably of the form shown and provided with a serrated surface 110

20 upon the side adjacent the rope and is pivotally mounted between the side frames upon the bolt 10. The outer extremity of the rope grip is pivoted at 13 between the 5 spaced side members of the rope locking lever and a pair of spaced downwardly depending links 22 are pivotally connected at their upper extremities to the bolt 13, the lower extremities of said 10 links being connected to the housing 23. A bolt 24 is passed through the lower extremities of the links 22 and through the outer extremities of a pair of spaced links 25 which are pivotally connected at 26 to the side flanges. A bolt 27 is slidably mounted through the housing 23 and provided with a coil spring 28 which bears against a fixed collar 29 upon the bolt, said bolt being arranged to enter the aperture 30 in the plate 31 upon the main frame when the parts are 15 in the unlocked position as shown in Fig. 1. A lever 32 is pivotally mounted upon the bolt 24, the upper extremity of said lever being provided with a forked end 33, which straddles the bolt 27 and receives the thrust of said bolt by engagement with the collar 29. The outer extremity of said lever carries a suitable eye or link 34 to which the 20 extremity of the elevating rope 35 is attached.

In reeving the carrier one end of the elevating rope 35 is connected to the eye 34, either by knotting or by use of a device such as the rope clamp 36. Extending from said 25 eye the rope passes downward and through the lifting head or heads of the fork, sling or other hay engaging device, and then upwardly from said hay engaging device and over the main sheave 9 and then outwardly 30 beneath the rope grip 19 and between the rollers 15 and 16 upon the rope locking lever. From this point the elevating rope extends downwardly at an angle to the side of the barn in which the carrier is mounted and 35 passes over the usual pulley mounted upon the barn wall and commonly known as the purlin pulley. This of course is common in all cross draft hay carriers and it is unnecessary to illustrate this pulley in the present 40 application.

It will be understood that the carrier is arranged to be moved laterally upon the track in the usual manner. The ordinary method of moving a cross draft carrier upon 45 a track is to attach a rope to each side of the carrier, said ropes extending away from the carrier upon each side and in a plane parallel with the track. One of these ropes passes over a pulley attached to some portion of 50 the side wall of the barn and a sand bag or other weight is attached to the end of the rope and the other rope passes over a suitable pulley at the other side of the barn and extends downwardly. This rope is 55 usually referred to as the shift rope or con-

veyer rope and is used to move the hay carrier upon the track, the sand bag acting as a counter-weight to move the carrier back to the original position when the shift rope is released. This is the usual arrangement of 70 shift rope and has no relation to this invention excepting that some means should be provided for moving the carrier upon the track.

The operation of a hay carrier embodying 75 the invention is as follows: The parts being in the loading position as illustrated in Fig. 1, it will be noted that the rope locking lever is in the raised position and the extremity of the bolt 27 is located through the aperture 30 in the main frame of the carrier, thus through the links 22 holding the rope locking lever in the raised position and maintaining the rope grip in unlocked position so that the fall of the elevating rope 80 may be brought down to the point of attachment of the load. When the load is attached and the elevating team which is attached to the free end of the elevating rope, is driven forward drawing the elevating rope forwardly, the load will be raised toward the carrier, the angle at which the elevating rope is located from the main sheave of the carrier to the purlin pulley causing the rope locking lever to be held 85 in the upward or unlocked position, allowing the main sheave to rotate. When the load has been carried up to the carrier and the elevating team stopped, the weight of the load will be sufficient to pull the lever 32 90 into the position shown in Fig. 3 releasing the bolt 27 from the aperture 30 in the main frame and moving the parts into the position shown in Fig. 3. It will be noted that when the parts are in this position the rope 95 grip 19 is held in tight engagement with the rope pressing the rope firmly against the brake 17 and holding the brake tightly against the main sheave, thus locking the sheave against rotation and preventing any 100 movement of the elevating rope. It will be seen that instead of merely gripping the rope as is usual in hay carriers the main sheave itself is locked against rotation. The load will thus be sustained during the travel 105 of the carrier along the track to the place of discharge of the load and in fact until the carrier is returned in the usual manner to the loading point. The shift or conveyor rope is then operated to move the carrier 110 along the track until it reaches the proper position over the mow. The sling or fork is then tripped in the usual manner allowing the hay to drop into the mow and the shift rope is operated in the opposite direction, 115 moving the carrier back along the track to the initial or loading point. The elevating rope is then given a quick pull straightening the said rope from the main sheave to the purlin pulley, raising the rope locking 120 125 130

lever and moving the parts into the unlocked position as shown in Fig. 1. The rope grip is thus held in the unlocked position and the brake is released allowing the main sheave to be rotated so that the fall of the elevating rope may be brought down to the point of attachment of the load.

I claim:—

1. A hay carrier provided with a main sheave, a locking lever pivotally connected to said carrier, a rope grip connected to said locking lever, a spring pressed bolt operatively connected to said locking lever for holding said locking lever in the raised position, means for withdrawing said bolt to allow the locking lever to be moved downward and an elevating rope connected to said bolt withdrawing means, and passing over the sheave and forming a fall, said elevating rope passing between the sheave and the rope grip and engaging said locking lever.

2. A hay carrier provided with a main sheave, a locking lever pivotally connected to said carrier, a rope grip connected to said locking lever, a sheave brake connected to said carrier, a spring pressed bolt operatively connected to said locking lever for holding said locking lever in the unlocked position, means for withdrawing said bolt, and an elevating rope connected to said bolt withdrawing means and passing over the sheave and forming a fall, said elevating rope passing between the rope grip and the sheave brake and engaging said locking lever.

3. A hay carrier provided with a main sheave, a locking lever pivotally connected

to said carrier, a rope grip connected to said locking lever, a spring pressed bolt operatively connected to said locking lever for holding said locking lever in the unlocked position, a lever for withdrawing said bolt to allow the locking lever to be pulled into the locked position and an elevating rope connected to said bolt withdrawing lever and passing over the sheave and forming a fall, said elevating rope passing between the sheave and the rope grip and engaging said locking lever.

4. A hay carrier provided with a main sheave, a locking lever pivotally connected to said carrier, a rope grip connected to said locking lever, a spring pressed bolt operatively connected to said locking lever for holding said locking lever in the unlocked position, said carrier provided with an aperture adapted to receive the extremity of said bolt when the locking lever is in the unlocked position, a lever operatively connected to said locking lever for withdrawing said bolt from said aperture and an elevating rope connected to said bolt withdrawing lever, passing over the sheave and forming a fall, said elevating rope passing between the sheave and rope grip and engaging said locking lever and arranged to withdraw said bolt from said aperture allowing the locking lever to be pulled into the locked position causing said rope grip to clamp the elevating rope against said sheave.

In testimony that I claim the above, I have hereunto subscribed my name.

HENRY S. NUNAMAKER.
